UNITED STATES PATENT OFFICE.

PETER CHRISTIAN CARL FRIDERICHSEN, OF INDEPENDENCE, MISSOURI.

DESIGN FOR A NOSE TILE.

Application filed March 24, 1927. Serial No. 21,309. Term of patent 14 years.

To all whom it may concern:

Be it known that I, PETER C. C. FRIDERICHSEN, a subject of the King of Denmark, residing at Independence, in the county of Jackson and State of Missouri, have invented a new, original, and ornamental Design for a Nose Tile, of which the following is a specification, reference being had to the accompanying drawing, forming a part hereof.

The figure is a perspective view of a nose tile, showing my new design.

What I claim is:

The ornamental design for a nose tile, as shown.

PETER CHRISTIAN CARL FRIDERICHSEN.
